AUTOMATIC REFLUX HEAD FOR FRACTIONATING COLUMNS

Peter N. Heere, Livingston, N.J., assignor to Distillation Engineering Company, Livingston, N.J.

Application July 16, 1954, Serial No. 443,871

2 Claims. (Cl. 202—161)

The invention herein disclosed relates to the control of reflux in fractionating columns.

Operation of these columns requires the provision of some means for controlling the reflux ratio, the ratio of product taken off to that of liquid, reflux, returned to the column.

The optimum operating condition in a column is reached when such reflux is returned at its boiling point.

Various methods have been employed, one involving removing the total stream from the column, measuring it and returning a reheated portion as reflux. Another system has included controlling the temperature of partial condensers and thus condensing back portion of the vapor stream as reflux while condensing the remainder as product in a subsequent condenser.

The boil-up rate in a column often fluctuates due to changes in feed stock, column pressure, steam pressure and other variables and since the examples mentioned are not independent of the boil-up rate, inaccuracies in the control of the reflux ratio have resulted.

Further inaccuracies result when the reflux is not returned exactly at its boiling point.

Controlling the reflux ratio, therefore, inside the column proper is highly desirable as external heat losses are prevented and because the reflux is then always returned exactly at its boiling point.

Difficulties have arisen, however, in such inside column control, since moving parts exposed to the leaching and corrosive action of solvent vapors will often fail to operate due to lack of lubrication.

Other objections have followed from use of electrical circuits such as electromagnetic coils around a distillation column, because of fire and explosion hazards.

Objects of the present invention are to provide an internal automatic reflux control unit improved to overcome objections and faults such as mentioned, operable under either vacuum or elevated pressures, and otherwise suited to present day requirements.

Particularly it is an object to enable moving parts to function while exposed to corrosive solvent vapors.

Special objects are to accomplish division of reflux and product by simple, accurately operating mechanism and in such manner that heat losses in the unit are minimized and compensated for with resulting highly accurate control of reflux ratio.

Further special objects of the invention are to accomplish all of the above in a single practical mechanical unit applicable to various size fractionating towers and in which necessary electrical circuits will all be enclosed and protected in fully explosion-proof condition.

Other desirable objects attained by the invention and the novel features of construction, combination and relation of parts comprising the invention are set forth or will appear in the course of the following specification.

The drawing accompanying and forming part of the specification is illustrative of a present commercial embodiment of the invention but structure and arrangement may be modified and changed as regards the immediate

illustration, all within the true intent and scope of the invention as hereinafter defined and claimed.

Fig. 1 in the drawing is a broken vertical sectional view of the automatic reflux head;

5 Fig. 2 is a top plan view of the same;

Fig. 3 is a diagrammatic view showing location of the reflux head in a distillation unit, indicating product and pressure equalizing lines;

10 Fig. 4 is a front elevation of the tilting funnel showing how it is flattened toward the lower end to spread the reflux in the form of a ribbon.

In the construction shown in Fig. 1, vapor from the column enters the bottom of the head 7 at 8, passing around the collection box 9 and through the vapor slot 10 under baffle 11, leaving at the top, at 12, to pass into the condenser, the latter indicated at 13 in Fig. 3.

All the vapor is condensed in the condenser and returns by gravity as liquid to the automatic head.

15 This condensed liquid is diverted by baffle 11 and drip lip 14 to a collection pocket 15 in the upper portion of the head.

The total liquid stream flows from collector 15 through an outlet tube 16 into a tilting funnel 17 which directs it either into section 18 or section 19 of collecting box 9, 20 the first of these delivering through tube 20 to the column and the second through withdrawal line 21 as product. Sections 18 and 19 of the collecting box are shown separated by a partition plate 22.

25 Direction of flow is governed by position of the tilting funnel 17 which is normally in the position shown, reflux to the column, when solenoid 23 controlling the same is deenergized.

30 Solenoid 23 when energized lifts core 24, pulling up rod 25 connected to arm 26 on rock shaft 27 rotating in bearings 28. The far end of rocker arm 26 then depresses link 29 connected with arm 30 on the axle 31 which forms the pivotal support for the funnel and which is journaled in bearings 32. This movement rocks the funnel to a position as indicated in broken lines, Fig. 1, to direct the 35 total stream to compartment 19 and out through withdrawal line 21 as product.

35 The reflux ratio is the ratio of time that the solenoid coil is not energized to length of time that it is. This ratio may be determined by the setting of the off and on 40 interval of an electrical timer installed in series with the solenoid coil, satisfactory timers being available for such purpose.

45 In order to withstand the corrosive action of solvent vapors the automatic reflux head may be constructed of a resistant alloy metal.

50 The solenoid core 24 may be composed of iron covered with a corrosion resistant alloy sheath, as indicated at 33, or it may be constructed of corrosion resistant magnetic alloy.

55 The solenoid supporting tube 34 which is extended upward from the side of the head and which may be of resistant alloy metal, is indicated as equipped with cooling fins 35 to prevent overheating of the solenoid when the automatic head is operating at high temperatures.

60 The solenoid housing 36 may be constructed with a removable cap 37 in an approved explosion-proof, Class I, Group D manner suitable for operation of electric circuits in a hazardous location.

65 The enclosure cap 37 is shown carrying a stop or projection 38. Parts 36, 37 and 38 are preferably constructed of iron or various alloys adapted to be readily magnetized and demagnetized. The use of such metals and stop 38 considerably increases the strength of the magnetic field around solenoid coil 23.

70 The bearings 28 and 32 for the rocker arm and for the funnel supporting axle are preferably constructed of graphite, this material being corrosion resistant to most

solvents and being self-lubricating. It is considered, however, that these bearings may be of other corrosion resistant materials such as plastics in the nature of "Teflon" polytetrafluoroethylene, precious metals and the like.

The entire funnel and bearing supports are shown mounted on a plate 39 removably seated in the bottom of the condensate collecting chamber 15 so as to be readily removable for inspection, cleaning or servicing.

The amount of travel of the tilting funnel is controllable in the illustration by adjustment of the length of the connecting link 25, this being shown as having a regulatable screw thread engagement at 40 in the end of the core 24.

The complete solenoid housing including outer portions of the supporting tube 34, are shown located outside of the column insulation and these, with the cooling fins 35, will condense vapors that reach up into these parts. The condensate which may thus form will be collected, together with liquid that flows down from the condenser in the collecting pocket 15 and thus be accurately divided by the tilting funnel.

The collecting box 9 is shown located well within the shell of the reflux head with a minimum cross-sectional area of metal present for conduction of heat away from the box, thus minimizing condensation of vapor and any loss of accuracy of reflux ratio. This is further facilitated by small cross-section of supporting struts 41 and minimum cross-section of withdrawal tube 21. The box itself, as shown, does not touch the shell of the reflux head.

Since the pressure of the vapor in the automatic reflux head may be somewhat higher than that at the top of the condenser 13, Fig. 3, it may be necessary or desirable to have an equalizing line 42 extending between the product outlet 21 and the condenser vent 43, and also a seal loop 44 in the product line, the latter to prevent vapor from blowing out through this line. The height of this seal loop should be sufficient to hold back vapor when the column is operating at maximum contemplated rate.

The invention provides a practical automatic reflux head in the form of a unit adapted for direct mounting in the column of large and small diameter fractionating towers. This unit may be readily constructed of available plate, pipe, tubing and other forms of metallic, ceramic, plastic or other materials. The adjustable mechanical linkage provides for accurate reflux ratio control. The parts particularly subjected to corrosive action are carried by a plate or base readily removable for inspection, cleaning or repair.

The graphite bearings provide corrosion resistant and self-lubricating support for parts operating in the corrosive atmosphere. The electrical parts are completely enclosed and protected against hazardous explosive conditions.

Heat losses in exposed parts are compensated for by collecting condensed material and conducting it back into the main liquid stream for accurate division, resulting in a higher degree of accuracy in reflux ratio control.

The internal collecting box is so arranged that any heat losses from it to the wall of the reflux head are minimized, with resulting higher accuracy in reflux ratio control. The adjustable core of the solenoid sheathed with protective alloy, is unaffected by corrosive solvent vapors.

While shown equipped with cooling fins, water or other cooled jacket may be provided on the solenoid tube to protect the solenoid from high temperatures such as sometimes may be present in the automatic reflux head.

The solenoid housing constructed of magnetic material and wholly enclosed, provides ample magnetic strength for the solenoid operation described.

The automatic reflux head disclosed is especially adaptable to vacuum, pressure or hazardous service, since no stuffing boxes or other potential leak sources are present in the construction.

What is claimed is:

1. A variable ratio automatic reflux head unit for assembly with a fractionating column comprising an open-ended upright cylindrical shell of a diameter corresponding to that of the column, said shell having means at its upper and lower ends for connecting same to the top of the column and to a condenser above the column to carry the complete boil-up from the column to the condenser; a collection box supported in the lower portion of the shell in substantially transverse relationship thereto and in spaced relation to the wall of said shell, said collection box having a substantially vertical partition mounted therein to separate same into separate reflux and product compartments, the reflux compartment having a vertical discharge outlet in the bottom thereof to discharge reflux collected therein directly into the column when the unit is in assembled relationship therewith, the product compartment having a laterally extending outlet immediately adjacent its bottom to permit the carry off of the collection product, a liquid receiving pocket transversely mounted in the upper portion of the shell and spaced above said collection box, the bottom surface of said liquid receiving pocket being provided with a discharge outlet which is substantially in vertical alignment with the partition of said collection box, downwardly extending tilting funnel means journaled at its upper end to the undersurface of said pocket and in registry with the discharge outlet present therein with the lower end of said funnel means terminating at said collection box at a point above said partition therein, said funnel means having a swinging movement to carry liquid from the liquid receiving pocket to the reflux and product compartments at opposite sides of said partition, an inwardly extending and downwardly inclined baffle plate secured to the wall of said shell above the plane of said liquid receiving pocket and extending inwardly from the wall of the shell and terminating at a point above and over said liquid receiving pocket and forming a vapor slot therewith for passing vapors over the pocket, and electro-mechanical means mounted externally on the sidewall of said shell and operatively connected with said tilting funnel means to actuate same to effect the desired tilting operation and to vary the arc of swinging movement of the funnel means whereby reflux and product are developed from the total vapor flow from the column and reflux is returned to the column at boiling point unaffected by external conditions and a substantially constant reflux ratio is maintained essentially independent of external heat losses.
2. A variable ratio automatic reflux head unit for assembly with a fractionating column comprising an open-ended upright cylindrical shell of a diameter corresponding to that of the column, said shell having means at its upper and lower ends for connecting same to the top of the column and to a condenser above the column to carry the complete boil-up from the column to the condenser; a collection box supported in the lower portion of the shell in substantially transverse relationship thereto and in spaced relation to the wall of said shell, said collection box having a substantially vertical partition mounted therein to separate same into separate reflux and product compartments, the reflux compartment having a vertical discharge outlet in the bottom thereof to discharge reflux collected therein directly into the column when the unit is in assembled relationship therewith, the product compartment having a laterally extending outlet immediately adjacent its bottom to permit the carry off of the collection product, a liquid receiving pocket transversely mounted in the upper portion of the shell and spaced above said collection box, the bottom surface of said liquid receiving pocket being provided with a discharge outlet which is substantially in vertical alignment with the partition of said collection box, downwardly extending tilting funnel means journaled at its upper end to the undersurface of said pocket and in registry with

the discharge outlet present therein with the lower end of said funnel means terminating at said collection box at a point above said partition therein, said funnel means having a swinging movement to carry liquid from the liquid receiving pocket to the reflux and product compartments at opposite sides of said partition, an inwardly extending and downwardly inclined baffle plate secured to the wall of said shell above the plane of said liquid receiving pocket and extending inwardly from the wall of the shell and terminating at a point above and over 10 said liquid receiving pocket and forming a vapor slot therewith for passing vapors over the pocket, said baffle plate terminating in a drip lip over said pocket, and a solenoid supported externally on the sidewall of said shell, a core operable by said solenoid and operating connections extending from said core to said tilting funnel means adjustable to vary the arc of swinging movement of the funnel whereby reflux and product are developed,

from the total vapor flow from the column and reflux is returned to the column at boiling point unaffected by external conditions and a substantially constant reflux ratio is maintained essentially independent of external heat losses.
